Attorney

UNITED STATES PATENT OFFICE.

ERNEST E. SCHLAVIN, OF WRENSHALL, MINNESOTA.

FOUNTAIN SCRUBBING-BRUSH.

1,270,217.

Specification of Letters Patent. Patented June 18, 1918.

Application filed September 26, 1917. Serial No. 193,241.

To all whom it may concern:

Be it known that I, ERNEST E. SCHLAVIN, a citizen of the United States of America, residing at Wrenshall, in the county of Carlton and State of Minnesota, have invented new and useful Improvements in Fountain Scrubbing-Brushes, of which the following is a specification.

The present invention has reference generally to improvements in that class of inventions known as brushing and scrubbing and more particularly relates to a fountain scrubbing brush.

This invention has for its principal object to provide a device of the above character wherein the construction is such that the liquid supply is arranged in communication with the brush bristles while the flow of liquid thereto is controlled by valve means manually operable from a point at the outer end of the handle enabling the user to readily regulate the amount of liquid dispensed when using the brush.

More particularly this invention embraces the provision of improved means acting in conjunction with the valve means and mounted in the handle for operating the valve means so as to consequently control the flow of liquid onto the brush bristles when the brush is in use.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be exemplified in the construction hereinafter described and the scope of the application of which will be indicated in the appended claims.

45 The invention is clearly illustrated in the accompanying drawings, in which:—

Figure 1 is a longitudinal view of the device partly in section;

Fig. 2 is a top plan view thereof.

50 Similar characters of reference are employed in all the above described views, to indicate corresponding parts.

Referring now, more particularly, to the accompanying drawings, there is provided a brush body 1 of a rectangular configuration the under surface of which is provided with

a plurality of recesses 2 for accommodating brush bristles 3 which depend from the body. The body is further provided centrally thereof with a vertical opening 4 for a purpose that will presently appear. A tubular handle 5 has its inner end exteriorly threaded and removably arranged in the correspondingly formed recess 6 in the body while the handle projects upwardly at an angle 65 therefrom, as indicated, being formed adjacent its inner end with an opening 7 for a purpose that will hereinafter become apparent. A sectional knob indicated in its entirety by the numeral 8 is formed on the outer end of the handle 5 and in the present instance preferably consists of the inner section 9 formed with the handle, being in effect an enlargement of the outer end of the handle, the outer edge thereof being reduced as at 10 for receiving the end 11 of the outer removable section 12 which, in the present instance, is provided in its outer portion with spaced openings 13 also for a purpose that will presently appear.

With a view toward providing the improved liquid supply a cup-like container 14 is employed and is designed to receive a fluid cleaning compound and is closed through the instrumentality of a removable cap 15. A nipple 16 is led from the bottom of the container 14 and is mounted in the enlarged upper portion of the opening 4 in the body, as indicated in Fig. 1, the flow of liquid to the brush bristles being controlled through the instrumentality of suitable valve means indicated in its entirety by the numeral 17. The valve in the present instance consists of a body 18 journaled transversely through the nipple 16 and also provided with a transverse bore 19 therethrough. A stem 20 continues from one end of the valve and terminates at its outer end in a cross head 21 provided adjacent its opposite ends with openings 22. Of course by rotating the valve to align the opening with the nipple liquid will readily flow from the container 14 to the bristles but upon reverse rotation of the body 18 the flow through the nipple will be prevented.

As intimated, improved means have been provided for operating the valve means from a point adjacent the outer end of the handle to enable the user to conveniently operate the valve means and control the flow of liquid to the brush bristles while using the brush. In reducing this feature of the

invention to practice a rod 23 is arranged transversely through the side walls of the inner section 9 of the knob 8 while pivotally mounted on this rod are a pair of handle levers indicated in their entireties by the numeral 24. Each handle lever is pivotally mounted at a point midway its ends on the rod and is formed with an angularly bent lower end 25 terminating in a loop 26. The opposite end of each lever constitutes a handle portion 27 in the upper end of which is formed a knob 28. In this connection it will be observed that subsequent to the mounting of the levers the outer section 12 of the knob on the handle 5 is arranged so that the handle portions 27 will pass through the openings 13 when the section is being applied. Suitable flexible elements such as wire cables 29 are now employed and have their upper ends connected to the loops 26 and their main portions arranged within the tubular handle as indicated in Fig. 1 the outer portions being extended through the opening 7 and thence through the eyes 30 carried by the upper surface of the body preparatory to being connected in the openings 22 adjacent the opposite ends of the wing-like handle of the valve which when in a closed position is disposed horizontally of the nipple. By this arrangement it will be appreciated that by pressing either of the knobs 28 of the handle portions 27 a pull will be exerted on the corresponding cable and by reason of the arrangement of the cable the valve body will be partially rotated in one direction so as to be opened and of course the valve may be closed by merely depressing the other knob 28 when it is so desired. In this manner, as is apparent, the operator can readily control the flow of liquid through the device when using the same.

It is believed that in view of the foregoing description a further detailed description of the operation of the invention is

entirely unnecessary. Likewise it is believed that the advantages of the invention will be readily apparent.

As many changes could be made in the above construction and many apparently widely different embodiments of this invention could be made without departing from the scope thereof, it is intended that all matter contained in the above description or shown in the accompanying drawings, shall be interpreted as illustrative and not in a limited sense. It is also to be understood in this connection that the language used in the following claim is intended to cover all the generic and specific features of the invention herein described and all statements of the scope of the invention which as a matter of language might be said to fall therebetween.

Having thus clearly described the invention, what is claimed as new and desired to be secured by Letters Patent is:

A fountain scrubbing brush including brush means, liquid containing means mounted thereabove, valve means between the container and brush means for controlling the flow of liquid to the brush means, a cross head for adjusting the valve means and having openings therein, a tubular handle connected to the brush means and provided with openings, a sectional knob on the handle provided with openings, a pair of handle levers pivotally mounted in the knob and having their outer handle portions arranged through the openings of the knob, guide eyes mounted on the brush means beneath the valve handle, and cables arranged in the tubular handle and having their upper ends connected to the inner ends of the handle levers and their lower portions trained through the openings in the main handle and the guide eyes and connected to the openings in the wing-like handle.

In testimony whereof I affix my signature.

ERNEST E. SCHEAVIN.
